Primary Examiner — Darcey E Gottschalk

(57) **CLAIM**

The ornamental design for a bottle lid, as shown and described.

DESCRIPTION

FIG. 1 is a front, top perspective view of a bottle lid showing my new design;

FIG. 2 is a rear, bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a front, top perspective view thereof, showing an opened bottle lid; and,

FIG. 10 is a rear, bottom perspective view thereof.

In the drawings, the broken lines show portions of a bottle lid that form no part of the claim.

1 Claim, 10 Drawing Sheets
